UNITED STATES PATENT OFFICE.

HERBERT SYMONDS, OF ST. LOUIS, ASSIGNOR OF ONE-HALF TO CHARLES D. MOODY, OF WEBSTER GROVES, MISSOURI.

CORNICE-BRAKE.

SPECIFICATION forming part of Letters Patent No. 394,145, dated December 4, 1883.

Application filed August 3, 1883. Serial No. 281,900. (No model.)

To all whom it may concern:

Be it known that I, HERBERT SYMONDS, of St. Louis, Missouri, have made a new and useful Improvement in Cornice-Brakes and 5 Analogous Sheet-Metal-Forming Machines, of which the following is a full, clear and exact description.

The improvement relates to that part of the machine which is used in gaging the 10 movement of the bending-bar. Prior to the date thereof what is termed a "quadrantal gage" had been employed, consisting of a quadrantal arm provided with a stud adapted to be adjusted and held at any desirable 15 point upon the arm, and when so adjusted forming a stop projecting into the plane in which the bending-bar lever moves and limiting its progress. The operator adjusted the stop upon the arm to correspond to the 20 angle it was desired to form in the metallic sheet and then turned up the bending-bar, carrying the sheet until the bending-bar lever encountered the stop, and when a second bend was required the stop was readjusted 25 upon the arm, the sheet readjusted in the machine, and the bending-bar again turned up until its lever encountered the stop, and so on, shifting the stop with every change in the angles required; or if a number of 30 sheets were to be formed similarly and it was desired to retain the stop in one position until all the sheets had been bent to the angle corresponding to the position of the stop before proceeding to the forming of the second bend or angle, the sheets were successively inserted in and successively removed 35 from the machine every time a bend or angle was formed. By either procedure considerable time and labor were required, and 40 the operation was a tedious one.

To lessen the difficulty referred to and to provide for operating a cornice-brake more expeditiously than hitherto has been attainable is the aim of the present improvement, 45 which consists in contriving the stop so that, while it may be adjusted and fixed at any desired point upon the quadrantal arm, a portion of it—namely, that portion which projects into the field of the movement of the 50 bending-bar lever and is the part with which

the lever comes in contact—is made readily removable from said field, thereby enabling several stops to be attached at the same time to the quadrantal arm, and respectively at those points thereon which correspond to the 55 various angles or bends of the cornice to be shaped and to be used successively without changing the positions of the stops upon the quadrantal arm or without withdrawing the sheet from the brake until the entire cornice, 60 or until several angles, at least, of the cornice, have been formed—that is, by being able to shift the movable portion of the stop into and out of the field of the movement of the bending-bar lever the operator is enabled to 65 manipulate the stops to bring said movable portion of any one of them into position to gage the movement of the bending-bar lever, or out of position, so that the bending-bar lever can be moved past it and against some 70 other stop in the series, all substantially as is hereinafter more fully set out and claimed, aided by a reference to the annexed drawings, making part of this specification, and exhibiting the most desirable mode of carrying 75 out the improvement, and in which—

Figure 1 is a side elevation of a cornice-brake having the improvement. Only that portion of the brake is shown which is needed for an understanding of the improvement, 80 and the improved portion of the construction is shaded to more readily distinguish it. Fig. 2 is a front elevation of the parts of Fig. 1; Fig. 3, a section on an enlarged scale on the line 3 3 of Fig. 1; Fig. 4, an end elevation of 85 one of the stops; and Fig. 5, a view analogous to that of Fig. 1, but showing a modification of the improvement.

The same letters of reference denote the 90 same parts.

The cornice-brake A (shown in Figs. 1 and 2) represents any of the familiar constructions in use, saving as the construction may be modified or supplemented by the improvement in question.

B, Figs. 1 and 2, represents the bending-bar lever.

C represents the quadrantal arm, past which the lever B is moved, as indicated by the positions of the lever shown in full and in 100

broken lines, respectively. The arm C is slotted at c.

D D' D² represent a series of the stops used to gage the movement of the lever B. The essentials of the stop are a holder portion, d, by which the stop is fastened to the arm C, and another portion, d', attached to said portion d, but so that the portion d' can be turned, swung, slipped, drawn, thrust, or otherwise moved to bring it into or out of the path in which the lever B is moved—that is to say, there are several ways of attaching the stop to the arm C, several ways of constructing and of uniting the portions d' and d², and several ways of moving the portion d' into and out of the way of the lever B. What I consider as desirable as any is shown in the annexed drawings, and especially in Figs. 3 and 4. The portion d consists of a bolt, d², passed through the slot c and provided with a nut, d³. The bolt d² has a head, d⁴, to come against the inner face of the arm C, and by screwing the nut onto the bolt, so as to draw the inner end of the nut against the outer face of the arm C or against an interposed washer, d⁵, as shown, the parts d² d³ can be clamped to the arm C. The bolt d² is perforated longitudinally at d⁶, and the nut d³ is extended longitudinally and is chambered at d⁷. The portion d' of the stop is in the form of a bolt, and it is held in the perforation d⁸ of the bolt d² and in the chamber d⁷ of the nut d³.

In Fig. 3 the bolt d' is shown closed into the holder, and when thus closed no obstacle is presented to the lever B; but by moving the bolt d' endwise it can be moved outward from the holder into the position shown in the broken lines, Fig. 3, and in the full lines in Fig. 2, and in the last-named position it extends across the pathway of the lever B. To hold the bolt d' in either of its positions against being accidentally displaced, the spring d⁹, Fig. 3, is employed. The spring at its outer end is attached to the shell of the nut, substantially as shown, and its outer portion, d¹⁰, is upon the outer side of the nut, and its inner portion, d¹¹, is folded upon its outer portion, but is contained within the chamber d⁷, and when the bolt d' is closed the bend d¹¹ of the spring comes against the inner side of the head d¹² of the bolt, and when the bolt d' is opened out the curved end d¹³ of the spring comes against the outer side of the bolt-head d¹². This serves to stay the bolt sufficiently to keep it from being jarred out of place, but not so as to prevent the bolt from being intentionally moved.

In operating the stops D D' D², &c., they

are clamped to the arm C at the proper points thereon to suit the respective angles or bends 60 to be made in the sheet E. That one of the stops to be used first—say the stop D—has its bolt d' pushed out, as shown in Fig. 2, and the bolts d' of the other stops, D' D², are closed. The bending-bar is then upturned 65 until its lever B encounters the bolt d' of the stop D and the desired angle or bend is formed in the sheet. The bending-bar and lever are then turned down. If the next stop to be used is the one D², the bolt d' of that stop is 70 pushed out and made to gage the movement of the lever B, and the second angle or bend is formed in the sheet. If the next stop to be used is the one D', then the bolt d' of the stop D² is closed into its holder, and the bolt 75 d' of the stop D' is thrust outward and made to limit the upward movement of the bending-bar lever and a third angle or bend is formed in the sheet, and so on, closing into their respective holders those bolts d' which do not 80 for the time being require to be used and opening out the bolt d' of that stop which is required to be used. By this means many angles or bends can be formed readily in a sheet without removing it from the machine 85 and without shifting the stops upon the arm C.

A modification of the construction within the principle of the improvement is applying the stops D D', &c., to the quadrantal arm, as before, but attaching the quadrantal arm to 90 the journal of the bending-bar, so as to revolve with it. This is shown in Fig. 5. The bolts d' of the stops in such case are contrived to encounter a suitable shoulder, and so that the angles or bends shall be properly 95 made in the sheet E.

I claim—

1. The combination of the arm C and the stops D D', &c., said stops consisting of a holder portion, d, for securing the stop to said arm, and a movable portion, d', substantially as and for the purpose described.

2. The combination of the arm C, the bolt d², perforated as described, the chambered nut d³, and the bolt d', substantially as described.

3. A sheet-metal-forming machine having a slotted quadrantal arm, C, and one or more stops, D D', &c., said stops being adjustable upon said arm and each having a movable portion, d', substantially as and for the purpose described.

HERBERT SYMONDS.
